UNITED STATES PATENT OFFICE.

CHARLES J. SEEGER AND THOMAS D. CLARKE, OF NEW YORK, N. Y.

DESIGN FOR A BATTERY-BODY.

SPECIFICATION forming part of Design No. 32,450, dated April 3, 1900.

Application filed November 4, 1899. Serial No. 736,835. Term of patent 7 years.

To all whom it may concern:

Be it known that we, CHARLES J. SEEGER and THOMAS D. CLARKE, citizens of the United States, residing at New York, in the 5 county of New York and State of New York, have invented and produced a new and original Design for Battery-Bodies, of which the following is a specification.

The accompanying drawing, forming part 10 of this specification, represents a perspective view of our novel design for a battery-body.

As shown in the drawing, the leading or material feature of our design is a cylindrical body A, upon the lower end of which is an annular bead a, beneath which are three successively-enlarged annular extensions b, c, and d, presenting the appearance of the lower being overlapped by the next higher. The 15 annular extensions b and d are slightly concave in form, and the annular extension c is convex.

Upon the upper end of the cylindrical body A is an annular bead a', above which is a frusto-conical annular body or extension e, the periphery of which is concaved. The upper 20 surface e' of the extension e is flat, and within

the border or rim thereof is a somewhat-smaller disk f, above which is an upwardly-ranging approximately-conical post g. Upon the top of the post g is a flat disk or circular 30 plate B, upon the upper surface of which, at opposite sides thereof, are circular bodies or cylindrical sections h, h', h², h³, h⁴, and h⁵. At the center of the disk or circular plate B is an upwardly-ranging cylindrical post C, 35 with two smaller studs i, one at either side thereof.

Having fully described our invention, we claim as new and desire to secure by Letters Patent—

The design for a battery-body as herein 40 shown and described.

In testimony that we claim the foregoing as our invention we have signed our names, in presence of the subscribing witnesses, this 1st 45 day of November, 1899.

CHAS. J. SEEGER.
THOMAS D. CLARKE.
